UNITED STATES PATENT OFFICE.

FREDERICK H. TIMSON, OF SHARON, MASSACHUSETTS.

DESIGN FOR A GAITER OR SIMILAR ARTICLE.

Application filed September 20, 1922. Serial No. 3,774. Term of patent 3½ years.

To all whom it may concern:

Be it known that I, FREDERICK H. TIMSON, a citizen of the United States of America, residing at Sharon, in the county of Norfolk and Commonwealth of Massachusetts, have invented a new, original, and ornamental Design for Gaiters or Similar Article, of which the following is a specification, reference being had to the accompanying drawing, forming a part thereof.

In said drawing, Fig. 1 is a side elevation of a gaiter viewed from the right; and Fig. 2 is a similar view from the left.

I claim:

The ornamental design for a gaiter or similar article, substantially as shown.

Signed by me at Boston, in the county of Suffolk and Commonwealth of Massachusetts, this fifteenth day of September, 1922.

FREDERICK H. TIMSON.
